UNITED STATES PATENT OFFICE.

RICHARD C. STEWART, JR., AND WALLACE A. STEWART, OF COVINGTON,
KENTUCKY.

FENCE-RAIL.

SPECIFICATION forming part of Letters Patent No. 743,046, dated November 3, 1903.

Application filed June 29, 1903. Serial No. 163,507. (No model.)

To all whom it may concern:

Be it known that we, RICHARD C. STEWART, Jr., and WALLACE A. STEWART, citizens of the United States, residing in Covington, in the county of Kenton and State of Kentucky, have invented certain new and useful Improvements in Iron Fence-Rails; and we do declare the following to be a clear, full, and exact description thereof, attention being called to the accompanying drawings, with the reference characters marked thereon, which form also a part of this specification.

This invention relates to improvements in the construction of iron structures, like fences, and where they consist of angularly-arranged members held in place on each other by one set of said members passing through perforations in the other. Referring more particularly to fences, these members are represented as to one set by the pickets and as to the other by the rails, the former passing through these latter and through perforations in them. They are now held in place against slipping in these perforations by various contrivances, and often merely a tight fit, increased by swaging, is sometimes relied upon to hold them in place. Owing to the slenderness of these members there is not much room and material at disposal to provide for more substantial methods of joining, and such means as rivets, screws, and bolts are objectionable as being more or less unsightly and out of place on fences, especially where they are more or less ornamental.

To overcome the objections of an imperfect joint and to provide means which permit a substantial connection to be made between the members to be joined—that is, in a fence between the pickets and the rail—and without appreciable increase in manufacturing cost is the object of our invention. The same consists of the construction, arrangement, and means as hereinafter described and claimed, and as illustrated in the accompanying drawings, in which—

Figure 1 shows in perspective view a section of an iron fence consisting of vertical pickets held in place by horizontal rails and in the manner prescribed by our invention. In its outward appearance such a fence does not differ from a customary fence. Fig. 2 is

an enlarged cross-section through one of the rails at a point where one of the pickets passes through it. Fig. 3, also enlarged, shows a portion of such a rail in longitudinal section, the connection of the engaged parts being completed. Fig. 4 is an under side view of such a rail portion and shows the manner in which our invention is carried out in practice. Figs. 5, 6, 7, and 8 show various modified profiles of fence-rails, all applicable in the use of our invention.

In the drawings, 10 represents the pickets held in position by rails 11, the two together constituting the fence. There may be any number of rails, and the pickets may all be of the same length or of alternatively different lengths, as shown. The upper ends of the pickets may be finished more or less ornamenteally and provided with points or knobs 12, and the fence may be held in upright position by means as shown at 13. The rails consist of the flat portion 11^a, having one but more usually two flanges 11^b to obtain stiffness and rigidity, the whole together forming a so-called "channel-iron." The pickets are held in upright position bypassing through perforations 14 in them and in which they closely fit, all as best shown in Fig. 2. The formation of these rails of ordinary channel-iron endows them, even with limited thickness of the metal, with stability more than sufficient for requirements and purposes, and the metal is therefore made not thicker than really necessary, the object being to reduce weight and save metal where such is not needed. The limited thickness of the usual channel-rail, while not objectionable as impairing the strength of the rail, reduces, however, the possibility of providing substantial connecting means to hold the picket against slipping within the perforation 14 of the rail, all as already referred to, and which is due to the limited extent of opposite surfaces coming in contact between picket and rail, owing to the limited thickness of the ordinary channel-rail. To overcome these objections and to provide additional metal, we increase the thickness of the same where the picket passes through the rail, the increase being on the inner or under side of the rail and between the flanges 11^b thereof and as shown at 11^c in

Figs. 3, 4, 5, 6, 7, and 8. This increase does, however, not extend laterally to flanges 11^b, the object being to produce grooves 11^a, the purpose of which will be presently explained.

5 This increase in thickness also increases the contact between opposite surfaces of the engaged parts, as best shown in Figs. 2 and 3, so that, provided the pickets are fitted tightly, the mere increased frictional contact fur-
10 nishes in itself a means of engagement fairly secure. The increased thickness furthermore provides a possibility of using other additional means, like rivets or screws, should such be desired, so as to render the engagement be-
15 tween pickets and rails absolutely secure against displacement and slipping. The grooves 11^a, provided at each side of this increased part and between the edges of such part and flanges 11^b, permit access for the ap-
20 plication of such means. However, this lat-
ter method referred to is hardly necessary in fences, and sufficient hold of the pickets is ob-
tained by a riveting or calking procedure and whereby part of the metal of the increased
25 portion 11^c thereof and between flanges 11^b is swaged against the pickets, as shown at 15 in Fig. 3, the procedure being shown in Fig. 4. A suitable tool 16 is used, and the metal of rail 11 from its increased part 11^c and
30 where it surrounds or abuts against the pick-
ets is driven tightly against and partly into these latter, as shown in Fig. 3, the manipu-
lation being usually called "swaging" or
"calking." The driven metal being free to
35 spread by yielding into grooves 11^a, it is clear
that the effect of the force exerted by the de-
livered hammer-blows extends deeper into
the metal, so that an extensive engaging con-
40 tact between the opposite metal surfaces
takes place. At the same time these grooves,
by permitting any metal crowded away from
the pickets yield into them, prevent disfigur-
ing of the rail. This manner of holding the
45 pickets is rigid and secure and sufficient for
all practical purposes in a fence and does
away also with previous notching of the pick-
ets, as is done in some fence constructions.
The additional metal for these purposes being
50 on the under side of the rail with reference to
its position in the finished fence is therefore

not visible, and as far as appearance is con-
cerned our improved rail does not look any
different from or heavier than the usual chan-
nel-rail. This metal may be given different
profile-lines, some modifications of it being 55
shown in Figs. 5 to 8. The shape of this out-
line is, however, immaterial, the main point
being the additional metal, to increase cor-
respondingly the contact between the oppo-
site surfaces of the engaging parts and the 60
groove on each side of it, to permit the
swaged metal to yield and spread laterally.
In this respect our invention differs from the
rails disclosed in Patent No. 428,291, where
no grooves are provided between the in- 65
creased part and the lateral flanges into
which the metal displaced by the swaging
action may yield. It also differs from Pat-
ent No. 262,879, where metal furnished by in-
ternal flanges is bent into notches previously 70
provided in the pickets. In our construction
no notched pickets are required, the connec-
tion being obtained by merely driving the
metal from the increased metal on the under
side of the rail tightly against the pickets, 75
any metal which is displaced by the driving
or swaging action yielding laterally into the
grooves between this increased metal and
the lateral flanges.

Having described our invention, we claim 80
as new—

A fence-rail consisting of a flat outer part
and of angular flanges at the edges thereof,
the part between the flanges being perforated
to receive fence-pickets and of a thickness 85
which provides on the inner side of the rail
sufficient additional metal to be driven and
swaged against the pickets to hold them se-
curely in place and grooves provided at each
90 side of this increased part and between the
angular flanges into which part of the metal
driven against the pickets may yield and
spread laterally.

In testimony whereof we hereunto set our
signatures in the presence of two witnesses. 95
